Patented Feb. 20, 1912.

UNITED STATES PATENT OFFICE.

HIRAM W. MONTGOMERY, OF SANTA MONICA, CALIFORNIA.

SUSPENSORY.

1,017,897.

Specification of Letters Patent. Patented Feb. 20, 1912.

Application filed May 16, 1910. Serial No. 561,759.

To all whom it may concern:

Be it known that I, HIRAM W. MONTGOMERY, a citizen of the United States, residing at Santa Monica, in the county of Los Angeles and State of California, have invented a new and useful Suspensory, of which the following is a specification.

Objects of the invention are: ease with which clean parts may be substituted for soiled ones; perfect fit when new and adjustability when the elastic portions become stretched by usage; also convenience in carrying a supply of new sacks.

In devices of the kind heretofore in use, the sack is either entirely unsupported in the rear or the supports passing entirely or partially around the legs of the wearer produce undue pressure when the wearer assumes some positions and insufficient pressure when he assumes other positions, and no attempt has previously been made to supply sufficient elasticity and yet to minimize the amount of elastic necessary.

An object of my invention is to avoid the foregoing difficulties and this I do by constructing a suspensory with a single under-strap, adapted to pass between the legs of the wearer and by constructing the belt and supporting strap partially of elastic and partially of inelastic sections fastened together.

Other objects and advantages may appear in the subjoined detail description.

The accompanying drawings illustrate the invention.

Figure 1 is a perspective view of the suspensory detached, the parts being in the position they occupy when the appliance is in use. Fig. 2 is a fragmental sectional detail on line approximately indicated by α^2 , Fig. 1. Fig. 3 is a detail of the cast-off and the suspending loop, looking in the direction of the arrow from 3, Fig. 1, the cast-off being open and the suspending loop detached. Fig. 4 is a detached view of two pieces of fabric which may be stitched together to form the sack. Buttons are shown on the two upper corners of the larger piece. Fig. 5 is a perspective view of the slidable link detached. Fig. 6 is a detached view of the sack case with sack

therein. The cover of the case is shown removed.

The suspensory comprises a belt 1, an under-strap 2 and a sack 3. The belt 1 is preferably composed of both elastic and inelastic materials of cotton or silk to suit the wearer, the side elastics 4, 5, being only long enough to give the requisite amount of tension which may be adjusted from time to time by buckles 6 when the elastics 4, 5, become stretched by usage. The elastics 4, 5, are preferably sewed to an inelastic back piece 7 of webbing or other fabric, elastic 4 being slidably connected by link 8 and elastic 5 being slidably connected by link 9 and a hook 10, with an inelastic front piece 11, which may be sewed to a cast-off 12 having suitable means as the snaps 13 for fastening the flaps 14 that secure a suspending loop 15 having flat ends 16 provided with button holes 17 for the reception of buttons 18 sewed to the upper corners of the sack 3. The middle portion 19 of the suspending loop 15 is preferably rounded and the entire suspending loop may be of webbing or the flat ends alone may be of webbing and the middle rounded portion 19 of leather. The construction with webbing alone is preferred.

The ends of the loop 15 will preferably be left blank in the devices as delivered to the user so that the wearer may cut the button holes after having ascertained, in any convenient manner, as by temporarily pinning the ends of the loop to the sack, the most satisfactory position for them.

The cast-on and suspending loop together form a ready means of temporarily disconnecting the sack from the belt while on the wearer, which is necessary because of the preferred closed construction of the sack.

A slidable link or bar 20 is provided at its ends with eyes 20' for the reception of the back piece 7, upon which said link is slidably mounted and between which back piece and link there passes an elastic connection 21. To prevent undue wear of the elastic the link 20 is provided with a rearwardly and downwardly rounded flange or lip 22, over which the elastic 21 is looped. The

purpose of the slidable connection of the elastic 21 with the belt 1 is that it may accommodate itself to any variation in the lengths of the sides by reason of the elastics 4, 5, stretching unequally or when the adjusting buckles 6 are operated to take up slack in either or both of the elastics 4, 5.

The elastic 21 is provided with a buckle 23 for the purpose of adjustment when the elastic 21 stretches with usage, and is further provided with a hook 24 for connection at its lower end with a ring 25 which is sewed to one end of a piece of tape 26 or the like, the other end of the tape being sewed to the lower end of the sack 3. The tape 26 is made sufficiently long to bring the hook 24 and ring 25 to a point about one inch above the lower extremity of the spinal column; thus the elastic 21 is made as long as possible, while the hook and ring are kept from beneath the wearer when he is seated.

The elastic 21 and the tape 26 together form the under strap 2, which supports the sack 3 from the rear and is connectible and separable at the hook and ring 24, 25, in putting the suspensory on and off and also so that the sack may be quickly detached from the elastic when the sack is to be laundered. The provision of detaching means at both ends of the sack allows the removal of same with ease and the substitution of clean sacks, which may be carried in small boxes or cases *a*, one of which is illustrated in Fig. 6, the cover *b* being removed to expose an extra sack 3' rolled within its case, the combination being compact and perfectly sanitary.

A short piece of webbing 27 is looped over the back piece 7 of the belt 1 and when the suspensory is in wearing position, illustrated approximately by Fig. 1, the webbing 27 lies immediately in front of the elastic 21 and between it and the wearer's body so as to protect the elastic from perspiration.

The sack 3 may be knit as one complete piece or may be cut from any suitable cloth, which has preferably been shrunk; a two-piece pattern may be employed for this purpose, a resulting sack in its developed and unseamed condition being illustrated in Fig. 4, in which 28 is the outer part and 29 the inner. In seaming up, the angular edge 30 of the end 31 is placed in a position corresponding to the diagonal dotted line 32 of the opposite end or lap 33. When the ends 31, 33, have been joined, the oval opening 34 is slightly smaller than the piece 29 which is then sewed at its edge 35 to the edge 36 of the said oval opening.

In practice the wearer will be supplied with a belt having the cast-off at the front of the elastic back strap 21 and the webbing protector 27 connected with the belt as shown and will also be supplied with a requisite number of the sacks 3 to each of

which an under-strap 26 is secured, each of said under-straps being provided with a ring 25; and each of said sacks being provided with the buttons 18. There will also be supplied one of the detachable suspending loops 15.

To supply the device with a fresh sack, the belt with the back strap 21, protector 27, and the cast-off 12 with the suspending loop 15 fastened therein, may be passed around the body and fastened with the links 8, 9 and the hook 10. The wearer may apply the sack by passing the ring 25 back between his legs, hooking it onto the hook 24, bringing the sack into position for use, and buttoning the buttons 18 into the eyes 17. The appliance is thus adjusted in place and when it is desired to displace it this may be done by simply releasing the hook and ring fastening means 24, 25, which allows the under-strap 26 to drop forward; whereupon the sack 3 may be drawn out of the way.

The back strap may be adjusted relative to the cast-off by sliding the link 20 along the back piece 7, thus bringing the back strap 21 diametrically opposite the cast-off, or to one or the other side of the center of the back as the form to be fitted may require.

The sack 3 may be formed in any well-known manner of forming concavo-convex pieces of woven fabric, and consists of a concavo-convex member of a general triangular form provided at its upper corners with fastening means as the buttons 18, and terminating in a rounded tip 37 to which the under-strap 26 is sewn. By employing a sack of this form the suspensory will be fitted in such a manner as to give ease and comfort.

Whenever it is desired to do so, the sack and under-strap 26 may be detached and may be replaced with a fresh sack and strap, while the removed sack and strap are being laundered.

I claim:—

1. A suspensory comprising a belt having a back section, a link provided at its ends with eyes through which said back section slides, an elastic back strap suspended from said link, a sack suspended from the front of the belt, an under-strap fastened to the lower end of the sack, hook and ring means for connecting the under-strap with the back strap, and an inelastic protecting strip in front of the back-strap.

2. A suspensory comprising a belt, a cast-off at the front of the belt, a suspending loop in the cast-off, a triangular concavo-convex sack connected at its upper corners with the ends of the suspending loop, an under-strap fastened to the lower end of the sack and means for detachably connecting the back end of the under-strap with the back of the belt.

3. In a suspensory the combination with
a belt, of a link provided with two eyes slid-
ably mounted on the belt, a strap looped
around the belt between said eyes, and a
5 piece of elastic looped around the link
whereby the elastic is protected by the strap
from contact with the person.

In testimony whereof, I have hereunto set

my hand at Los Angeles, California this 3rd
day of May 1910.

HIRAM W. MONTGOMERY.
